UNITED STATES PATENT OFFICE.

FRANK A. LITTLEFIELD, OF NASHUA, NEW HAMPSHIRE.

VALVE APPARATUS.

SPECIFICATION forming part of Letters Patent No. 624,511, dated May 9, 1899.

Application filed April 22, 1898. Serial No. 678,459. (No model.)

To all whom it may concern:

Be it known that I, FRANK A. LITTLEFIELD, of Nashua, county of Hillsborough, State of New Hampshire, have invented an Improvement in Valve Apparatus, of which the following description, in connection with the accompanying drawings, is a specification, like letters and figures on the drawings representing like parts.

This invention has for its object the production of a valve apparatus particularly adapted for high-pressure service, whereby the great power necessary to open large valves of usual construction is obviated, the fluid-pressure being utilized to balance the valve, and I have herein so constructed the apparatus embodying my invention that whether the pressure be high or low the power necessary to operate the valve is substantially that necessary to overcome the friction of the controlling member in its stuffing-box.

The novel features of my invention will be hereinafter described in the specification and particularly pointed out in the claims.

Figure 1 is a vertical sectional view of one embodiment of my novel valve apparatus, the main valve being closed. Fig. 2 is a similar detail, but showing the controlling means in position to effect the opening of the main valve by fluid-pressure; and Fig. 3 is a view similar to Fig. 1, with the parts in position ready to effect closure of the main valve.

The case or shell A is herein shown as provided with an inlet A' and an outlet A², and the case is divided by a diaphragm A³, having a fluid-passage A³ therethrough, the edge of the opening being shown as upturned to form the main valve-seat a⁴.

The case A is in the present instance of my invention provided with an extension or chamber B, communicating by an opening a with the case, the cap C at the opposite side of the valve-seat being extended at C' to provide guide-bearings c c' for the actuating stem of the controlling means, to be described, a suitable stuffing-box C² being located at the outer end of the tubular extension of the cap.

The main valve is preferably made as a centrally-apertured disk b, having a central depending exteriorly-threaded hub b' and a

downturned peripheral flange b², a ring b³ of soft metal or other suitable material being firmly held within the flange against the under side of the disk b by a flanged sleeve b⁴, screwed onto the hub b', the annulus b⁵ resting on the seat a⁴ when the valve is closed. This construction makes renewal of the annulus a very simple matter, so that when the same becomes worn it can be removed and a new ring inserted without necessitating renewal of the other parts.

The lower end of the hub b' is shown as cored out to receive the reduced end d² of a tubular stem d, passing loosely through the opening a and into the chamber B, said stem having secured to or forming a part of it a piston D within but not necessarily fitting tightly the chamber B, the bore of the stem coinciding with that of the hub and extending entirely through the piston D, the shoulder d' of the stem limiting its upward movement relatively to the hub.

By removing the cap of the valve-case it will be seen that the main valve may be removed bodily from the case, the stem d sliding out from the hub b' at such time.

If steam or other fluid under pressure in the valve-case be permitted to pass beneath the piston, several different effects may be produced—that is, by making such exposed area of the piston enough greater than the opposite exposed area of the main valve fluid-pressure on the piston will operate to lift the main valve from its seat. If the two areas referred to are substantially the same, the fluid-pressure on the main valve will be in equilibrium, and to unseat the valve only sufficient power to overcome friction will be required, as in the present case. On the other hand, by making the area of the main valve greater than the opposed area of the piston the force required to unseat the valve may be varied as desired.

In the embodiment of my invention shown herein the fluid under pressure passes into the chamber B beneath the piston D through the hollow stem d, and such passage of the fluid is controlled by a valve operated from the exterior of the valve-case. To this end an annular upturned flange b⁴ on the upper

face of the disk b is threaded to receive a nut b^5 , which surrounds the enlarged head a' of a stem a^2 , extended through the bearings $c c'$ and the stuffing-box C^2 , said stem projecting 5 beyond the latter to be moved manually. Below the nut b^5 the head a' is annularly flanged, as at a^3 , and recessed or cupped out in its end at a^4 to receive an auxiliary or controlling valve, shown as a ball a^5 , loosely attached to 10 the head by a pin a^6 , the central hole in the disk b preferably being slightly beveled at a^7 to form a seat for the auxiliary valve, it being seen that the head a' has a limited reciprocating movement between the disk b and 15 the nut. Holes 15 in the flange b^4 permit the entrance of fluid from the case and beneath the head a' and through the tubular stem d when the auxiliary valve a^5 is unseated, as in Fig. 2, the loose attachment of the latter permitting it to freely adjust itself to the seat a^7 . When the main valve is closed, as shown in 20 Fig. 1, the water, steam, or other fluid enters the case A at the inlet A' and fills the case above the diaphragm A^X and passes through 25 the holes 15 into the space between the head a' and disk b and also on top of the auxiliary valve a^5 , maintaining the latter seated, and thereby closing communication between the piston-chamber and the valve-case at the 30 inlet side of the valve. The opening through the disk b is of the same diameter as the external diameter of the stem a^2 , so that whatever the pressure of the fluid the stem and its head a' are balanced, and in order to operate the auxiliary valve only sufficient power 35 to overcome the friction in the stuffing-box is necessary.

In the operation of the apparatus shown to open the main valve the stem a^2 is lifted to 40 unseat the auxiliary valve a^5 , so that the steam or other fluid can pass freely down the hollow stem d into the chamber B beneath the piston D , the surface of the latter being shown herein as slightly greater than the surface of the 45 main valve on the inlet side exposed to the pressure of the fluid, such pressure tending to maintain the valve seated, the greater area being necessary, because the piston does not fit tightly in the chamber B . The piston thus 50 having the greater exposed surface, the fluid pressure upon its under side will tend to slightly overbalance the pressure on the main valve, but not sufficiently to open said main valve, such movement of the latter being readily effected by sufficient power to overcome 55 friction applied externally to the stem a^2 .

In Fig. 3 the main valve is shown unseated; but by slight inward pressure on the stem a^2 sufficient to overcome friction the balanced 60 main valve will be seated, and finally the auxiliary valve will be moved to its seat, so that communication through the stem d between the chamber B and the inlet side of the main valve seat is shut off, as shown in Fig. 1.

65 My invention is not restricted to the precise

construction and arrangement herein shown, for the same may be varied or rearranged without departing from the spirit and scope of my invention.

Having fully described my invention, what 70 I claim, and desire to secure by Letters Patent, is—

1. An apparatus of the character specified, comprising a case having a valve-seat therein, a coöperating main valve, fluid-pressure-actuated means to mechanically balance pressure on the inlet side of the valve, and a manually-operated controlling device for said means, said device also acting to open or close the valve. 80

2. An apparatus of the character specified, comprising a case having a valve-seat therein, a coöperating main valve, a fluid-pressure-actuated piston connected with the valve by a detachable hollow stem provided with a valve-seat, and a controlling-valve for the seat in the stem, operative from the exterior of the case, to control the operation of the main valve. 85

3. An apparatus of the character specified, comprising a case having a valve-seat therein, and a piston-chamber communicating with the case, a main valve movable in the case, a piston reciprocable in said chamber, a detachable hollow stem connecting said valve 95 and piston, whereby fluid can pass from the inlet side of the former to the opposite side of the latter, a controlling-valve, a seat therefor on said stem, all wholly within the case, and means operative from the exterior of the 100 case to control the movement of the main valve.

4. An apparatus of the character specified, comprising a case having a valve-seat therein, a coöperating main valve having an attached 105 hollow stem, a fluid-pressure-operated piston connected with said stem, an auxiliary valve to open or close the opening through said stem, and a manually-operated stem connected with and having a limited movement independent of the main valve, the auxiliary valve being supported and moved by the stem. 110

5. In an apparatus of the character specified, a case having a valve-seat within it, a coöperating main valve comprising a disk 115 having a central hollow hub and a peripheral flange, an annular removable member adapted to be inserted within the flange, means mounted on the hub to retain said member in place, and means to operate the valve, said annular member engaging the valve-seat when the valve is closed.

6. In an apparatus of the character specified, a case having a valve-seat within it, a coöperating main valve having a detachable 125 hollow stem extended through the seat, a piston on the other end of the stem, a chamber in which it is movable, an auxiliary valve-seat on the main valve at the opening of the stem, a ball-valve to coöperate therewith, and 130

a balanced stem to which said ball-valve is loosely connected, said stem having a limited movement independent of the main valve, unseating of the ball-valve permitting passage of fluid from the casing to the chamber below the piston, to thereby balance the main valve by fluid-pressure on the piston.

In testimony whereof I have signed my name to this specification in the presence of two subscribing witnesses.

FRANK A. LITTLEFIELD.
